CLAIM

The ornamental design for a case for portable electronic computing device, as shown and described.

DESCRIPTION

FIG. 1 is a front perspective view of a case for portable electronic computing device showing my new design.

FIG. 2 is a rear elevational view thereof.

FIG. 3 is a front elevational view portion thereof.

FIG. 4 is a right elevational view thereof.

FIG. 5 is a left elevational view thereof.

FIG. 6 is a top plan view thereof; and,

FIG. 7 is a bottom plan view thereof.

The broken lines depict features of the case for portable electronic computing device that form no part of the claimed design.

1 Claim, 5 Drawing Sheets
